UNITED STATES PATENT OFFICE.

JAMES F. McELROY, OF ALBANY, NEW YORK, ASSIGNOR TO THE CONSOLIDATED CAR HEATING COMPANY, OF WHEELING, WEST VIRGINIA.

TEMPERATURE-REGULATOR.

SPECIFICATION forming part of Letters Patent No. 462,503, dated November 3, 1891.

Application filed May 14, 1891. Serial No. 392,747. (No model.)

To all whom it may concern:

Be it known that I, JAMES F. McELROY, a citizen of the United States, residing at Albany, in the county of Albany and State of New York, have invented certain new and useful Improvements in a Temperature-Regulator, of which the following is a specification, reference being had therein to the accompanying drawings.

This invention relates to new and useful improvements in temperature-regulators; and it consists in the peculiar construction of the actuating mechanism designed to transmit motion from the thermostat to the device to be operated, such as the valve or damper.

The invention further consists in the peculiar construction, arrangement, and combination of the various parts, all as more fully hereinafter described.

In the drawings, Figure 1 is a front elevation of my improved device. Fig. 2 is a vertical central section thereof. Fig. 3 is a cross-section on line $\alpha\alpha$ in Fig. 1.

A is the supporting-frame provided with suitable means for attaching it to a wall in a room or car in which the temperature is desired to be maintained at or near a fixed point. This frame is provided at its top with an outward-extending frame or bracket B, to which are pivoted the depending levers C C'. Between these levers is a thermostat of any desired construction, that which I preferably employ being shown in the drawings, and consisting of an expansion-chamber formed by two circular disks secured together at the edges and containing within any suitable expansible material. I preferably use some material which will vaporize at or about the temperature desired to be maintained. In the drawings, I have shown two of these expansion-chambers D D' separated at the middle by a block E and having secured to each side blocks F F', giving a wide bearing for the disks to bear against as the material within

expands. These blocks or hubs F F' are provided with screw-threaded stems G G', respectively, which are oppositely screw-threaded and engage in correspondingly-threaded apertures in blocks H H'. These blocks are provided with pintles I on the side, which enter suitable apertures in the levers.

The levers are made in two parts a b, secured together by means of bolts or screws c, which clamp the blocks H H' between them, the halves of the levers being centrally recessed to allow the insertion of the blocks, as plainly shown in Fig. 1. J J' are pivots upon which these levers turn.

K is a lever secured to one of the blocks or hubs H H', extending to the side of the frame and so arranged that it can be turned up or down to adjust the levers to or from each other by turning the screw-threaded stems in the blocks. At the lower end these levers connect to a connecting-rod K' by means of toggle-levers L and cross-head M. This connecting-rod extends to the valve or damper to be operated, which valve or damper is held normally in a certain position by the action of a spring N, bearing at one end against the guide-bearing O of the frame and at the other end against the nut P, adjustably secured upon the rod K'. The expansion of the thermostat will separate the levers C C', and through the toggle-levers L will move downwardly the connecting-rod K', overcoming the tension of the spring N. As the heat in the room increases and the thermostat continues to expand, it will bring the levers L more nearly to the vertical position, increasing the power in proportion to the amount of expansion. This is especially desirable in high-pressure steam-heating apparatus.

It is evident that my thermostat and the actuating-levers may be inverted from the position shown in the drawings, and the toggle-levers may be made to incline toward the actuating-stem instead of from it, so as to lift the valve to shut it instead of moving it downward, as would be the case in the construction illustrated.

The object of pivoting the blocks H H' to the levers is to prevent any strain upon the thermic cells due to change in angular position between such cell and the levers.

What I claim as my invention is—

1. In a temperature-regulator, the combination of the frame, a thermostat, two levers between which said thermostat is secured, and connections from said levers to the device to be operated, substantially as described.

2. In a temperature-regulator, the combi-

nation of the frame, a thermostat, two levers between which said thermostat is secured, a connecting-rod, and connections between said levers and the rod, substantially as described.

3. In a temperature-regulator, the combination of the frame, a thermostat, two levers between which said thermostat is secured, a connecting-rod, and toggle connection between said rod and levers, substantially as described.

4. In a temperature-regulator, the combination of the frame, a thermostat, two actuating-levers on opposite sides of the thermostat, a connecting-rod, a head on the rod, and toggle-levers connecting the head and actuating-levers, substantially as described.

5. In a temperature-regulator, the combination of the frame, two levers pivoted thereto, a thermostat secured between said levers, and right and left hand screw-threaded stems on

said thermostat engaging with said levers, substantially as described.

6. In a temperature-regulator, the combination of the frame, the thermostat having side projections, and the levers on opposite sides of the thermostat composed of two parts clamped upon said side projections, substantially as described.

7. In a temperature-regulator, the combination of the frame, the thermostat having screw-threaded stems on opposite sides, the blocks with which said stems engage, and the levers on opposite sides of said thermostat, to which said blocks are pivoted, substantially as described.

In testimony whereof I affix my signature in presence of two witnesses.

JAMES F. McELROY.
